STREET LAMP HEAD

Micheline Garbarini, 54 Rue du Mans,
Courbevoie, France

Filed Sept. 12, 1960, Ser. No. 62,124

Claims priority, application France Mar. 11, 1960

Term of patent 14 years

(Cl. D48—31)

Fig. 1

Fig. 2

Fig. 3

FIGURE 4 is a side elevational view of a modified form of the street lamp head shown in FIGURES 1, 2, and 3, the side not shown being substantially the same,

I claim:

The ornamental design for a street lamp head, as shown and described.
